UNITED STATES PATENT OFFICE

ALEXANDER McMILLAN, OF CHELAN, WASHINGTON.

BASE-BALL APPARATUS.

1,114,012.

Specification of Letters Patent. Patented Oct. 20, 1914.

Application filed January 3, 1914. Serial No. 810,195.

To all whom it may concern:

Be it known that I, ALEXANDER McMILLAN, a citizen of the United States, and a resident of Chelan, in the county of Chelan 5 and State of Washington, have invented certain new and useful Improvements in Base-Ball Apparatus, of which the following is a full, clear, and exact specification.

This invention relates to game apparatus, 10 and particularly to apparatus for mechanically pitching a ball and returning it to the batter, as in batting practice or as a sort of amusement.

One of the principal objects of this invention is to provide means for regulating or varying the speed at which the ball is pitched by the mechanical pitching device, said means being operated from a position near where the batter stands.

Another object is to combine the device for resetting the discharging device with the means for varying the speed at which the ball is discharged by said device, thus reducing the number of parts of the mechanism, 25 and making it possible for the device to be set for a different speed by the single operation of resetting the device for pitching the next ball. Thus each successive ball discharged or pitched may be at a different speed without requiring any additional operation to that of resetting after each discharge for the next. This feature of the device will be found very valuable in batting practice for familiarizing the players with 35 sudden changes of pace, and will also serve as a source of considerable fun where the apparatus is placed in amusement parks, inasmuch as the change in speed can be effected in resetting the discharging mechanism without the knowledge of the batter who is unfamiliar with the apparatus, and such change in speed will, therefore, take him completely by surprise.

A further object is to facilitate the return 45 of the ball after each discharge and to control the times of the discharges so that they can take place either when the batter wishes, and is ready for them or, if desired, when he is not expecting them, as when the apparatus, 50 is used for amusement purposes.

Other objects will become apparent as the description proceeds.

The invention will be first hereinafter described in connection with the accompanying drawings, which constitute a part of this specification, and then more specifically de-

fined in the claims at the end of the description.

In the accompanying drawings, wherein similar reference characters are used throughout the several views to designate corresponding parts: Figure 1 is a broken side elevation of an apparatus constructed in accordance with my invention, Fig. 2 is a broken top plan view thereof, Fig. 3 is a detailed front elevation of the ball returning device, partly in section, Fig. 4 is a side elevation of the discharging device on an enlarged scale, together with the lower end of the returning device, the resetting and speed-varying mechanism also being shown, Fig. 5 is a detailed plan view of the end of the discharging arm which carries the adjustable fingers, Fig. 6 is an enlarged detailed view, partly in section, of the locking lever which holds the discharging arm in set position and also serves as a trigger or trip for releasing said arm when the ball falls onto the same, and Fig. 7 is a partial section of a modified construction of the apparatus having a vertical screen or ball arresting structure instead of the inclined or sloping screen illustrated in Figs. 1 and 2.

In the drawings, A, A designate the sides of a screened inclosure arranged in front of the plate B and extending a suitable distance longitudinally and vertically. These sides preferably diverge away from the plate, and are made of woven wire or other suitable material. Across the wider end of the inclosure, which is also farthest from the plate B, there is placed an inclined ball-arresting screen C at the lower edge of which is formed a gutter or trough D inclined to and preferably extending through one side A of the inclosure. A cover E of woven wire or other suitable material is arranged preferably over the entire inclosure, as illustrated in Fig. 1.

In front of the inclined screen C and about midway between the sides A, A of the inclosure, the discharging or pitching mechanism is mounted on a suitable frame F. As best illustrated in Figs. 4, 5 and 6, said discharging mechanism comprises a pivoted lever or arm G pivoted at g to the frame F so as to swing in a vertical plane determined by the middle of the plate B. On the upper end of the arm G there is an adjustable extension H corresponding to the fingers of a pitcher's arm. Said extension is preferably made in the form of a loop

having two parallel portions h joined at their outer ends by a cross piece h' as illustrated in Fig. 5. A bolt h^2 passes through the parallel portions h and the end of the arm G serves to connect them together, and a nut h^3 on the end of said bolt may be readily adjusted to hold the extension at any desired angle with respect to the arm for regulating the trajectory of the ball.

10 The arm G is normally held in the position shown in Fig. 4 by a trigger or locking lever K pivoted at h to a part of the frame F and having a roller bearing L' , Fig. 6, to engage a hook g' on said arm G and to facilitate the release of said arm at the proper time. The lever K is further provided with a trip h^2 projecting up through the loop of the adjustable extension H. A bracket L projects from the end of the arm G substantially at right angles to the extension H for guiding the ball M onto said extension and against the trip. A heavy operating spring N is attached to the opposite end of the arm G, while a lighter resetting spring O is attached to said arm on the same side of its pivot with the adjustable extension H. The spring O is connected to the frame F. The spring N is connected to the upper end of a bell-crank lever P which is pivoted at p to the frame F and attached at its lower end to a rod R extended to a point near the plate B where it is in turn connected to the lower end of a lever S having a hand actuated pawl s adapted to interlock with a segmental rack S' . When the arm G is released in the manner to be presently described, the spring N will throw the upper end of said arm forward against the tension of the light spring O. In order to reset the arm, the lever S is turned to the right, Fig. 4, thereby relieving the tension of the spring N and permitting the spring O to draw the upper end of the arm back until it is locked by the gravity trigger K. After this has been accomplished, the lever S, is turned to the left, Fig. 4, until the desired tension has been placed upon the spring N. It will be readily seen that by varying the tension of said spring in this way, the speed of the ball discharged or propelled by said arm G, when next released, may be regulated. It will also be noted that this regulation or variation of the tension of the spring N is accomplished as a part of the resetting operation, so that, if desired a change in tension may be effected without knowledge of the batter, if he is unfamiliar with the apparatus.

60 In operation, when a ball is hit by the batter and strikes the screen C, it will roll down into the gutter or trough D and by reason of the inclination of said trough, will find its way to one side of the inclosure, see Fig. 3. The ball will then be picked up by an attendant and placed in a hopper T, Fig. 3 arranged next the cover E of the inclosure, from whence it finds its way into an inclined pipe U extending to a point nearly over the arm G. At that point the pipe 70 branches downwardly, at at u said branch terminating in a short inclined chute u' which is grooved to guide the ball as it emerges from an opening u^2 in the lower end of the branch pipe u . The lower end of 75 the chute u' is positioned to deliver the ball directly upon the trip h^2 in the crotch between the adjustable extension H and the guide bracket L. The weight or force of the ball striking the trip, causes the roller h' 80 to slip off of the hook g' , thus releasing the arm G which will then be swung forward by the spring N as already described. In order to have a number of balls always in readiness for use, the pipe U may be fitted 85 with a check lever V, Fig. 3, normally retained in the position illustrated by a spring W. This check lever normally prevents the balls from passing through the pipe U to the branch pipe u , so that said pipe U may 90 be utilized as a magazine, as illustrated. When a ball is to be pitched by the apparatus, the lever V is actuated by means of a flexible or other connection X extending into convenient reach of an attendant. Owing 95 to the fork v at the upper end of the lever V, only one ball will be released at a time, but by reason of the magazine, said balls may be released in rapid succession, if desired.

100 In Fig. 7, I have illustrated a modified form of screen C' to be arranged across the wider end of the inclosure in place of the inclined screen C. In this instance the screen is vertical instead of inclined, there being only a comparatively short curved portion c' at the bottom leading to the gutter or trough D' which is similar to the trough D.

Having thus described my invention, what I claim as new and desire to secure by Letters Patent of the United States is:

1. A mechanical baseball pitcher comprising means for discharging the ball, a spring for actuating said discharging means, a resetting spring adapted to come into play when the tension of the discharging spring is relieved, and means for relieving the tension of said discharging spring in order to permit the resetting spring to do its work and to subsequently renew the tension of said discharging spring to varying degrees.
2. A mechanical baseball pitcher comprising means for discharging the ball, a spring for actuating said discharging means, a resetting spring adapted to come into play when the tension of the discharging spring is relieved, a lever arranged adjacent the batter's position and operatively connected to said discharging spring for relieving the tension thereof in order to permit the reset.

ting spring to do its work and to subsequently renew the tension of said discharging spring, and means for retaining the lever at different positions to vary as well as 5 renew the tension of said discharging spring.

3. In a mechanical baseball pitcher, the combination with a pivoted pitching arm, of an adjustable extension on the end of 10 said arm for regulating the trajectory of the ball, said extension comprising two lateral portions embracing the end of the arm, and a cross piece bent out of the plane of 15 said lateral portions, a bolt passed through the end of the arm and the embracing portions of the extension, and a nut on said bolt for clamping said extension at various angles with respect to the arm.

4. In a mechanical baseball pitcher, the 20 combination with a pivoted pitching arm having a hook on its end, of a trip having a roller adapted to engage said hook for holding the arm in set position.

5. The combination with a mechanical 25 baseball pitcher, of a magazine adapted to

hold a plurality of balls, means to guide the balls from the magazine to the pitcher, a forked check lever for releasing one ball at a time from the magazine, resilient means for normally holding said check lever in 30 holding position, and means for operating said check lever from a distance.

6. The combination with a mechanical baseball pitcher, of means to guide a ball to 35 said pitcher, said means including a vertical tube, and an inclined chute at the lower end of said tube adapted to receive the ball at the bottom of said tube and deliver it onto the pitcher, said tube having an opening for 40 the passage of the ball onto the chute, which opening is only slightly larger than the ball, whereby said ball is compelled to roll smoothly down said chute.

In testimony whereof I have signed my 45 name to this specification in the presence of two attesting witnesses.

ALEXANDER McMILLAN.
